UNITED STATES PATENT OFFICE.

NORMAN P. FRASER, OF CARSONVILLE, MICHIGAN.

CHECK-CONTROLLED VENDING-MACHINE.

1,074,426.

Specification of Letters Patent. Patented Sept. 30, 1913.

Application filed July 6, 1912. Serial No. 708,031.

To all whom it may concern:

Be it known that I, NORMAN P. FRASER, a citizen of the United States, residing at Carsonville, in the county of Sanilac and 5 State of Michigan, have invented a new and useful Check-Controlled Vending-Machine, of which the following is a specification.

This invention relates to an improvement in check controlled vending machines.

10 The primary object of the present invention is to provide a machine for vending various sized articles, a further object of the invention being to provide a check controlled mechanism in which the check transmits the 15 movement of the operating lever, to the article releasing mechanism, with means whereby certain parts, may be interchanged in order that coins of different denominations may actuate the article releasing mechanism. 20 A still further object of the invention is to provide an article distributor, which may be readily filled with the articles to be vended, means being provided for closing the coin receiving slots when the supply of 25 articles to be vended, has become exhausted.

In the drawings, Figure 1 is a side elevation. Fig. 2 is a front elevation. Fig. 3 is a longitudinal section. Fig. 4 is an elevation, partly in section of the article receiving drum. Fig. 5 is a view of the coin controlled mechanism, the same being shown in inactive position. Fig. 6 is a view of the coin controlled mechanism, one of the plates which houses said mechanism being removed. 30 To more clearly show the mechanism, the article releasing mechanism being shown in its active position in dotted lines. Fig. 7 is a detail view of the interchangeable segments which contact with the coin to actuate 35 the article releasing mechanism. Fig. 8 is a detail view of the receiver, which operates the article holding drum. Fig. 9 is a detail view of the lever which normally maintains the drum against movement. Fig. 10 is a 40 front elevation of a portion of the mechanism, showing the offset 63 in contact with the offset 64 of the plate 22. Fig. 11 is a perspective view of the slot closure lever. 45

In the drawings, 10 designates a casing 50 which is provided with the hinged hood or cover 11, the casing 10 resting upon a base 12. A drum 14 is rotatably supported in the casing, said drum being provided with a plurality of pockets 15 in which the articles to be vended are placed, the drum being of a diameter slightly less than the

diameter of the housing formed by the casing and hood, the casing 10 being provided with a curved portion 16 which forms a continuation of the hood 11, the articles thus 60 being held within the pockets 15, as the drum is rotated. An article receiving trough 17 is secured to the casing 10, there being an opening 18 formed in the casing adjacent said trough through which the article to be vended is projected as soon as a 65 filled pocket has been brought in alinement with said opening by a movement of the coin actuated means. A gear 20 is secured to one end of the drum 14, this gear being provided with a number of teeth, equal to the pockets of the drum. The drum is normally held against rotation, in a manner which will be hereinafter described, the coin when deposited forming a connection between the 70 means actuated by the operating lever and means operating the drum, said rotating means when movement is imparted to same, releasing the mechanism which normally holds the drum against movement. 75

The check controlled mechanism is supported within the casing adjacent the end of the drum to which the gear is secured. This mechanism is supported between plates 80 21 and 22 which are secured to each other 85 and to the casing, the plate 22 being provided with offset edges 24 and 25 and together with the plate forms the coin chute, a magnet 69 being disposed adjacent said coin chute to draw slugs therefrom, the 90 terminals 26 and 27 of the plate, being disposed adjacent the coin receiving slot 40. A lever 28 is pivotally supported by the plate 22, said lever being provided with the lug 29 which is formed with teeth 30. A 95 bifurcated arm 31 is pivotally supported by a pin 32 which supports the lever 28, this arm being provided with a bifurcated terminal 33 which engages the lug 34 formed on the lever 28. The drum actuating lever 35 100 is connected to the terminal 36 of the lever 31. This lever 35 at its free end is provided with a dog 37 arranged to contact with the gear 20 to rotate the drum. It will thus be noted that as the lever is depressed and the 105 lever 35 is brought in the path of the gear, 20 the same will rotate the gear, to bring one of the article receiving pockets of the drum in register with the opening 18 in the casing. Pivotally supported at a point immediately below the toothed lug 29 of the 110 lever 28 is a segment 38, said segment being

provided with teeth 38^a and at either end with a cut away portion 39, the cut away portion at one end of said segment, being of a curvature, to embrace a ten cent piece 5 for instance, and the curvature of the other end being such as to embrace a five cent piece, it being noted that these segments may be interchanged, for various coins. This segment 38 is arranged to mesh with 10 the teeth of the lug 29. It will be noted that when a coin is deposited within the coin slot 40 of the casing the same will pass downward through the coin chute formed by the plates 21 and 22, the same lodging 15 between the segment 38 and the offset portion 32' of the lever 35. It will thus be noted that as the lever 28 is depressed, the same will rotate the segment 38, and the coin which is interposed between said segment 20 and the offset portion of the lever 35 and in contact with said lever lifting the lever 35, the dog contacting with the teeth of the gear carried by the drum to rotate the same until one of the article receiving pockets is in 25 register with opening 18 in the casing and allowing the contents of said pocket to be deposited within the article tray.

It will be noted that should a coin of a denomination larger than that intended to 30 operate the machine be deposited the same cannot assume the proper position between the segment 38 and the offset portion of the lever 35, and the machine will not operate. It will also be noted that if a coin 35 smaller than that intended to operate the mechanism should be inserted within the slot, the same will fall between the segment 38 and the lever 35, the depression of the lever 28, merely causing the tooth engaging lever 35 to ride upward, the lever not being pushed in contact with the teeth of the gear. It will thus be noted that a coin of the proper denomination must be inserted within the slot, in order that the 45 drum rotating mechanism may be actuated.

The drum is normally maintained against rotation by the lever 44, said lever being formed with a recess 45 which receives one of the teeth of the drum, the lever being 50 pivoted at the point 46, its terminal 47 being connected to the plate 22 by the spring 48, the said spring normally maintaining the lever in contact with the teeth of the gear, thus preventing the rotation of the drum. 55 An arm 62 extends from the lever 44 the curved offset terminal of said arm being actuated to release said drum. The lever 44 is provided with the offset 50 which is disposed in the path of the lever 35. The lever 35 is provided with a plurality of teeth 51 which as the lever is raised will contact with the offset 50 of the lever 44 locking the mechanism against return movement swinging the same on its pivot against the tension 60 of the spring 48 allowing the drum to

freely rotate, the offset 63 of the lever 35 riding on the offset 64 of the plate 22 the stroke of the lever 35 being such as to impart such a rotation to the drum that the same will move one pocket out of alignment with the opening 18. When the drum has moved this far the coin will have passed between the segment 38 and the offset portion of the lever 35, the lever returning to its normal position the lever 44 again engaging the drum and holding the same against movement, the coin being deposited on the curved terminal 70 of the arm 62 being maintained thereon until the mechanism is again operated.

In order that it may be known when the machine is empty and to prevent the depositing of a coin when the supply of articles has become exhausted a lever 53 is pivotally supported by the plate 22 adjacent the coin slot 40. This lever is provided with the offset portion 54 which when the lever is swung upon its pivot closes the slot 40. The terminal 58 of the lever is disposed in the path of the gear 20, one of the teeth of said gear being provided with a projection 59 which as the same passes the lever 53, contacts with the same to force it in a position to close the coin opening 40. This will indicate that the machine is empty and the slot will be maintained closed until the pockets are again filled with articles to be vended. When it is desired to refill the drum it is necessary to rotate the same and in order to release the lever 44 without operating the drum rotating mechanism, said lever is provided with the rod or extension 62 the looped terminal 70 of which extends within the housing 19, the said rod being moved to withdraw the lever 44 to release the drum when it is desired to refill the same.

The plate 22 is formed with an apertured offset 66 at each of its edges which forms guides for the rod 67, a coiled spring 67' embracing said rod and spacing its head 68 from the plate. This rod is actuated to contact with the offset 63 of the lever 35 to actuate the same in the same manner as if a coin had been deposited. Thus the drum 115 may be actuated by depressing the rod 67 and without depositing a coin. A mirror 71 is arranged above the coin receptacle 72 the mechanism being viewed through the glass 73 in the front of the cabinet. Thus 120 the purchaser may view the contents of the pocket before the coin is deposited.

What is claimed is:—

1. A check controlled vending machine, including a rotary article holder, a pair of plates disposed in spaced relation to each other, a manually controlled spring returned lever mounted between said plates and operable exteriorly of the machine, a toothed lug carried by said lever, a pivoted toothed

segment journaled between the plates and in co-active relation with the toothed lug of the lever, and a swingingly mounted holder engaging member carried by the inner end 5 of the lever and disposed in operable relation to the holder, said holder engaging member being normally spaced from the pivoted segment to receive a coin between it and such segment and whereby with the co- 10 operation of a coin and the depression of the lever, the article holder is rotated.

2. A check controlled vending machine, including a rotary article holder, a pair of plates disposed in spaced relation to each other, a manually controlled spring returned 15 lever mounted between said plates and operable exteriorly of the machine, a toothed lug carried by said lever, a pivoted toothed segment journaled between the plates and in co-active relation with the toothed lug of the lever, a swingingly mounted holder en- 20

gaging member carried by the inner end of the lever and disposed in operable relation to the holder, said holder engaging member being normally spaced from the pivoted 25 segment to receive a coin between it and such segment and whereby with the coöperation of a coin and the depression of the lever, the holder engaging member is elevated to cause the article holder to be rotated, and coacting 30 means carried by the holder rotating member and one of the plates for preventing a retrograde movement of the lever during the operation of the holder.

In testimony that I claim the foregoing 35 as my own, I have hereto affixed my signature in the presence of two witnesses.

NORMAN P. FRASER.
